Correction in Design Letters Patent No.
49,673.

It is hereby certified that in Letters Patent No. 49,673, granted September 19, 1916, upon the application of Henry W. Pleister, of Westfield, New Jersey, for a "Design for a Guy-Clamp," an error appears requiring correction as follows: In the grant and in the heading of the printed specification, assignment, strike out the residence of assignee; and that the said Letters Patent should be read with this correction therein that the same may conform to the record of the case in the Patent Office.

Signed and sealed this 24th day of October, A. D. 1916.
